UNITED STATES PATENT OFFICE

GEORGE A. JOHNSON, OF FAIRFIELD, CONNECTICUT, ASSIGNOR TO THE BRYANT ELECTRIC COMPANY, OF BRIDGEPORT, CONNECTICUT, A CORPORATION OF CONNECTICUT

INCLOSED TUMBLER SWITCH

Application filed May 17, 1928. Serial No. 278,447.

This invention relates to electric switches and in particular to the types known as snap and tumbler switches.

The objects of the invention are (1) to simplify and to economize the construction of the switch movement and of the housing therefor, (2) to render the operation of the switch more nearly silent than has heretofore been possible, (3) to make the operation of the switch quick and certain.

The preferred embodiment of the invention is illustrated in the accompanying drawings and is described hereinafter.

In the drawings—

Fig. 1 is a top plan view of the switch with the cover in place;

Fig. 2 is a sectional view on the line 2—2 of Fig. 1;

Fig. 3 is a plan view of the interior of the switch base with the cover and switch movement removed;

Figs. 4 and 5 are end views of the interior of the base on the lines 4—4 and 5—5 respectively of Fig. 3;

Fig. 6 is a view in section on the line 6—6 of Fig. 2;

Fig. 7 is an exploded view on an enlarged scale, of a part of the switch movement;

Fig. 8 is a detail perspective view of the connection between a movable contact member and its carrier;

Fig. 9 is a perspective view of the bridge member forming part of the switch movement;

Fig. 10 is a perspective view of the thumb piece.

The switch comprises three main parts, the base 11, the cover 12 and the switch movement.

The base 11 is of insulating material and has a well for the switch movement. On the corners of the base at the open end of the well are bosses 14 and, at the mid-portions of its opposite ends, larger bosses 15, these bosses

serving to position the cover. The inner bottom surface of the base is recessed at 16 to permit rocking of the contact carrier.

At one end of the base are fixed terminals 17 and 18 held in place by screws 19, 20 extending through the wall of the base from

the underside. The terminal piece 17 has a portion 21 extending upwardly and inwardly to form a knife-blade contact. Piece 18 has a similar portion 22 extending downwardly in the well in the base and inwardly as shown in Fig. 2.

At the other end of the base are terminals 23, 24 held in place by screws 25, 26 similar to screws 19, 20. These terminals are connected by a portion 27 which lies in the well and has an offset portion forming a contact blade 28. Extending inwardly and upwardly in the same manner as 21 is a contact blade 29.

Each terminal piece has a binding screw 30 for securing a lead wire. 65

The cover 12 is of moldable insulating material and is hollow. The ends of the cover are shaped to fit the bosses 15 and have shoulders to rest against the bosses 14. The cover has an aperture 31 for the thumb-piece and 70 slots for the contact blades 21 and 29.

The cover is held in position by ears 32 which serve also as a means for attaching the switch to a wall box, face plate or other support which commonly is used with switches of this type. For this latter purpose, holes 33 are provided in the offset attaching portions 34 and are enlarged to permit some freedom of positioning. The ears have offsets 35 which extend over the shoulders 80 formed by recesses 36 in the cover and thus, when the ears are secured in position on the base by the screws 37 which extend through holes 38 from the underside of the base, the cover is held tightly on the base. 85

Attention is called to the fact that the offsets 35 are bowed to give a certain resilience. This is to accommodate the slight differences in dimensions of the cover 12 and of the parts of the base which determine the relative levels 90 of the recesses 36 and the top of boss 15. These differences are avoidable only at considerable expense in manufacture but by the present construction are rendered immaterial. The resilience of the bowed offsets also gives a tighter clamping action and serves as a lock washer to keep the screws 37 from turning. It is to be noted that the ears should be held flat against the boss 15 to assure proper positioning of the attaching offsets 34 in 100

the same plane parallel to that of the plate to which they are secured.

The switch movement consists of a fixed bridge member 40 having arms 41 which rest on shoulders 15' on the bosses 15 and against the sides of these bosses. The cross bars 42 connecting the parallel bars 43 are so spaced that they rest snugly against the bosses 15 and on the shoulders 15'. The result is that the bridge piece is positioned on the base so as to be immovable laterally and, with the cover 12 in place, it is immovable in any direction.

Extending downwardly from the bars 43 are arms 44 having at their lower ends recesses forming fulcrums 45 for a rocking actuator 50. The walls of these recesses have convexly curved portions forming throats 46. These throats permit rocking of limited extent on the fulcrum surfaces and restrain the rocking member from excessive transverse play. Between the lugs 47 and the inwardly curved portion 48 of arms 44 and formed as recesses in the bridge bars 43 are fulcrums 49 having throats shaped similarly to throats 46.

The shape of the fulcrums is important. The fulcrum surfaces 45 and 49, the throat portions and the surfaces adjacent the throats 30 and connecting the respective throats and fulcrum surfaces are curved, as shown in Figs. 2 and 9. The members which rock on these fulcrums are flat (see 52 and 63) and are limited in their rocking movement by engagement on opposite sides with the curved surfaces adjacent the throats. By reason of the curves, this engagement is not sudden nor is it a direct surface upon surface engagement which would cause a noise as of a slap. 40 The engagement is gradual and to this, as well as to the material used for the carrier 60, described hereinafter, is attributed the silence of operation which characterizes this switch.

45 The rocking actuator 50 (see Figs. 2 and 7) is, in general shape, an inverted U. The down legs 51 have, near their lower ends, off-set lugs 52 which rest on the fulcrums 45 formed on the downwardly extending arms 50 of the bridge 40. Thus the actuator has a limited rocking movement on the fulcrums but is restrained by throats 46 from excessive transverse movement. Near their upper ends, the legs 51 have off-set or bowed portions 53 and 54 extending in opposite directions on the arcuate path of the actuator about its fulcrum for a purpose to be described. At the upper end of the actuator is a transverse member 55 having a stem on which is secured, in any known manner, a thumb-piece 56. The latter has curved shoulders 57 so that whatever the position assumed by the rocking actuator and thumb-piece, there is always a shield to prevent objects from entering the

switch by way of the opening 31 in the cover 12. (See Figs. 1 and 2.)

The contact carrier 60 is likewise of U shape but wider than the actuator 50 as shown in Figs. 6 and 7. It is made of insulating material, either fibrous or molded material of phenolic composition such as bakelite. Near the upper ends and on the inner sides of the legs 61 of this carrier are off-set lugs 62 from the lower portions of which extend the narrower lugs 63. Lugs 62 are spaced apart the same amount as the bridge bars 43 on the member 40 so that these lugs 62 rest in the fulcrum recesses 49.

As shown in Fig. 6, the carrier swings about the fulcrum 49 outside of the bridge member 40 with its transverse portion 64 clearing the down arms 44. The actuator 50, fulcrumed at 45, swings inside of the member 40 between bars 43. A coil spring 65 connects the transverse members 64 and 55 of the two rocking members 50 and 60. The effort of the spring draws the two rocking members together and against their respective fulcrums 45 and 49, thus holding the members in proper position without permanent securing means.

The lugs 63, extending inwardly from lugs 62, lie in the path of movement of the legs 51 of the actuator 50 (see Figs. 6 and 7) and adjacent the bowed portions 53 and 54 of the legs 51.

On the outer sides of the legs 61, near their upper ends but below the top or pivot ledges of lugs 62, are apertured off-set portions 66 for receiving the switch bars, one on each side of the carrier. The width of the slot is of greater extent than the thickness of the switch bar.

These switch bars 67 are stamped from conductive sheet material, each bar being made of two strips fastened together. Each bar has two arms 69, 70 and an enlarged central portion 71, the two arms being at an angle to each other (see Figs. 2 and 7) and the central portion 71 having a rectangular slot 72 with its long axis at right angles to arm 70 and of a size to receive one of the off-sets or ears 66 of the carrier 60. Each arm has at its end, separated contact portions (Fig. 7) for engaging both sides of the fixed knife blade contacts in the base 11.

To secure together the strips which make up each switch bar 67, the following method is preferred. Holes 77, 78, are punched in each strip, one hole 77 being left with the punched out material outstanding from the strip. With the other hole 78, the turned up material is cut away. The two strips may then be brought together with the turned up material of the hole 77 of each extending through the hole 78 of the other. The ends of the turned up portions are then spun or otherwise bent to lie over the other strip, thus firmly joining the two strips together. This effects an economy in the manufacture since 130

all strips may be made exactly alike and by the same operation.

The switch bars 67 are secured on the carrier 60 by clips 75 (Figs. 7 and 8) which are of spring material and are bent so that when forced through the apertures in the ears 66 on the side of the switch bars away from the carrier, the central part of the clip bears against the ear and the arms 76 of the clip exert a pressure against the switch bars holding them against the carrier 60.

This engagement between the switch bar and the carrier is such as to permit some swinging of the bars about the lugs 66 in a plane at right angles to that of the carrier. Such a floating mounting renders the bars self-aligning with respect to the fixed contacts, the flared ends 74 of the bars guiding the bars into fully closed position. This feature further simplifies the assembly in eliminating the need of great care and accuracy in positioning the contacts in each particular switch.

When the switch movement is assembled, the switch bars 67 are positioned with their arms parallel. Then, when in place in the base, as shown in Fig. 2, one switch bar connects the fixed contacts 28 and 21, the fixed contacts 29, 22 being disconnected. If the switch bar carrier is put in its other position by movement of the actuator, the fixed contacts 29, 22 are connected and the contacts 28, 21 are disconnected.

Various changes may be made in the arrangement of the fixed contacts or in the relative positions of switch bars. The arrangement shown is illustrative only and forms no part of the present invention.

The function and operation of the several parts are apparent.

The switch movement is a single unit which may be removed bodily from the base 12. It requires no securing means such as screws to hold it on the base but is positioned by the bosses 15 and held by the cover 12 which rests on the cross bars 42.

The cover is positioned by the corner bosses 14 and the end bosses 15, and is held to the base by the ears 32 which serve also as means for attaching the whole switch to a support such as a face plate or wall box.

The operation of the switch movement is responsive to movement of the thumb piece 56 and actuator 50, the spring 65 transmitting this movement to the carrier and giving a quick and certain movement of the switch bars 67. The actuator rests normally at either end position with either pair of fixed contacts connected by a switch bar. As the actuator 50 is moved, it carries the upper end of the spring 65 with it. When this end of the spring passes the dead center plane determined by the upper and lower pivots, 49 and 45, on the fixed bridge member 40, the effort of the spring on the rocking carrier causes the

carrier to swing about the fulcrums 49 and to snap into position against abutment 47 (assuming movement from the Fig. 2 position) thus swinging the switch bars 67 from the position in which fixed contacts 22 and 29 are connected, to that in which 21 and 28 are connected.

If, for any reason, the contacts do not separate easily under effort of the spring 65, further movement of the actuator causes either bowed portion 53 or 54, depending on the direction of movement, to engage one of the lugs 63. By this, a positive kick-off is effected. It is to be noted that the point of application of the kick-off effort is close to the pivotal axis of the carrier 60 and that, thereby, no bending of the carrier is brought about. The purpose of having the kick-off portions off-set is to delay their contact with lugs 63 until after the actuator has passed the dead-center plane where normally the spring should begin to draw on the carrier.

The use of insulating material for the carrier 60 has several advantages. Since the carrier strikes either abutments 47 or 48 on each movement, it follows that if both the carrier and the abutments are of metal an undesirable noise is created, audible in adjacent rooms especially where the walls are thin as is often the case. When insulating material, either fibrous or molded, is used, it is found that this noise is so slight as not to be objectionable.

A further advantage from using insulating material for the carrier is in the simple type of connection between the carrier and the switch bars which it makes possible. If the carrier is of metal, insulating pieces must be used between it and the switch bars. These pieces add to the cost and to the difficulty of assembly.

In the present structure, insulating pieces between the carrier and the switch bars are not needed. The securing clip 75 is very quickly put in place. The cost of materials, manufacturing operations and assembly operations is therefore reduced.

I claim—

In an electric switch, a carrier having an off-set portion, a switch bar slotted to receive said off-set portion, said portion having an aperture of greater extent than the thickness of said switch bar, and a spring clip extending through said aperture on the side of said bar away from the carrier and engaging said bar and said off-set portion to hold the bar against the carrier.

In testimony whereof I have signed my name to this specification.

GEORGE A. JOHNSON. 125
